(57) **CLAIM**

The ornamental design for a “lighting element for luminescent apparatus”, as shown and described.

DESCRIPTION

FIG. 1 is a top plan view of a lighting element for luminescent apparatus of our design,

FIG. 2 is a side view thereof,

FIG. 3 is a bottom elevation view thereof,

FIG. 4 is another side view thereof,

FIG. 5 is a cross-sectional view taken along the line 5—5 of FIG. 4; and,

FIG. 6 is a perspective view thereof.
